THREAD TENSION FOR SHUTTLE

Albert Cederlund and Kenneth J. Hall, Worcester, and Clifford Darwin, Paxton, Mass., assignors to Crompton & Knowles Corporation, Worcester, Mass., a corporation of Massachusetts

Filed Apr. 24, 1957, Ser. No. 654,806

7 Claims. (Cl. 139—217)

This invention relates to improvements in tensions for self-threading shuttles for weft replenishing looms and it is the general object of the invention to provide a shuttle tension which causes the first pick of the shuttle after replenishment to have the same tension as the subsequent picks have.

In weft replenishing looms of the bobbin-changing type reserve bobbins are held in some form of magazine provided with a thread holder for the weft ends which extend from the bobbin. At the time of a bobbin transfer or weft replenishing operation a reserve bobbin is pushed into the shuttle and on the first flight of the shuttle following transfer the thread unwinds from the new bobbin but is not completely threaded in the shuttle eye until the second pick of the shuttle. On the first shuttle flight after replenishment the weft is ordinarily under less tension than it is on subsequent picks of the shuttle.

It has been proposed heretofore to provide shuttle eyes which are intended to cause the tension on the first pick of the shuttle after transfer to be the same as on subsequent picks. Such shuttles may have a primary tension which acts on the weft for all flights of the shuttle and a secondary tension which acts on the weft only on the pick immediately following replenishment but as ordinarily made the secondary tension continues to have some effect on the tension of the weft after the shuttle is fully threaded.

It is an important object of the present invention to provide a shuttle having primary and secondary tensions and a guide post for the weft beyond the secondary tension with respect to the primary tension. On the second pick after transfer the weft is drawn away from the secondary tension to a position entirely clear of it and bends around the guide post and then extends to the delivery eye. The guide post and delivery eye produce a tension effect equal to that of the secondary tension so that all picks are under the same tension.

It is a further object of the invention to provide a secondary tension with two tension members one of which is located wholly above and the other behind the path which the weft traverses on the second and subsequent picks.

It is another object of the invention to provide a secondary tension so constructed that one of the tension members at least will have a horizontal surface which partially closes the thread passage of the shuttle eye to prevent upward escape of the weft from the shuttle.

In order that the invention may be clearly understood reference is made to the accompanying drawings which illustrate by way of example two embodiments of the invention and in which:

Fig. 1 is a plan view of part of a shuttle having the invention applied thereto,

Fig. 2 is a partial vertical section on line 2—2, Fig. 1,

Fig. 3 is an enlarged horizontal section on line 3—3,

Fig. 2,

2

Fig. 4 is an enlarged vertical section on line 4—4, Fig. 1,

Fig. 5 is a perspective view showing the two parts of the secondary tension separated and in a position which they might occupy before assembly in the shuttle eye.

Figs. 6 and 7 are diagrammatic views showing the path of the weft on the first and second picks of the shuttle immediately following a weft replenishing operation,

Fig. 8 is a diagrammatic view similar to Figs. 6 and 7 but showing a modified form, and

Fig. 9 is a view showing a second modified form in which the third guide post is on the front secondary tension member.

The shuttle S may have many of the ordinary features 15 characteristic of self-threading shuttles employed in weft replenishing looms such as a bobbin tip 1 and a bobbin compartment 2 for a bobbin B provided with a weft supply W. The shuttle is provided with a cavity 3 which receives a shuttle block 4 having front and back walls 5 and 6 respectively between which is a thread passage 7 extending lengthwise of the shuttle. In that part of the shuttle eye near the bobbin compartment 2 is located a primary tension PT comprising in the present instance inner and outer pairs of tension pads 8 and 9. These pads 25 may be of the usual type and extend vertically in the thread passage and are urged toward each other by springs 10. The lower ends of the pads 8 and 9 are guided by transverse pins 11 fixed to the shuttle. The usual adjustment for the springs 10 is afforded by screws 12 threaded into the shuttle block. The invention is not limited to the use of the two pairs of pads 8 and 9 since any form of primary tension can be used such for instance as a single pair of pads. The two pairs are shown herein because the invention has been adapted more particularly for use with elastic wefts such as cotton covered rubber and it is desirable to have sufficient tension at the primary tension to maintain the stretched condition of such weft.

The forward part of the shuttle is provided with a delivery eye D at the sides of which are the usual right and left tension posts 15 and 16 respectively. These posts may be supported in fixed position on the shuttle in any approved manner and they are spaced lengthwise of the shuttle as suggested in Figs. 1 and 3. There is 40 the usual thread passage 17 between the metallic part of the block 4 and the adjacent part 18 of the wood of the shuttle and the block has a downwardly and forwardly extending horn 19 of the usual construction forward of the thread passage. The shuttle body also has a shallow groove 20 extending toward the adjacent tip end of the shuttle and the block may be held in fixed position in the opening 3 by any approved means not shown herein.

In the operation of the part of the shuttle thus far described the thread W passes between the pairs 8 and 9 of pads and then extends forwardly to the delivery eye and from the delivery eye will extend either to the right or the left, depending upon the direction in which the shuttle is moving. On the first pick after replenishing operation the thread will extend in a relatively high position as shown in the dotted lines H, Fig. 2, along the groove 20 to the magazine thread holder (not shown) and on the return flight of the shuttle the thread is deflected downwardly and forwardly by the horn 19 so that it may enter the passage 17 and the delivery eye D and be in the lower position shown in dot and dash lines L. The matter thus far described may be of usual construction and operate in the usual manner.

In carrying the present invention into effect the shuttle 65 is provided with a secondary tension ST and also with a third guide and tension post 25 somewhat similar to the posts 15 and 16 but in back of the latter. The sec-

ondary tension includes front and back vertically extending tension members 26 and 27 respectively, the front member 26 as shown in Fig. 5 having a rounded surface 28 to fit into a semi-cylindrical upwardly and rearwardly cylindrical pocket 29 formed in the shuttle block 4. By means of a holding screw 30 the member 26 is held in its pocket in fixed position with respect to the block. The member 26 has a rearwardly facing vertical flat tension surface 31 extending into passage 7.

The second vertical tension member 27 is longer than the front member 26 and extends downwardly as at 32 and is perforated as at 33 to receive a guide pin 34 below member 26 extending transversely of and secured in the shuttle. The upper part of the rear tension member is bent rearwardly as at 35 and fits into an opening 36 in the block 4. A compression spring 37 normally urges the rear member 27 forwardly against the flat surface 31 and a screw 38 threaded into the block provides means for varying the force exerted by the spring 37. The line of action of spring 37, as is apparent in Fig. 5, is intermediate the top and bottom of the vertically extending surface 31. The rear member 27 may in fact be very similar to the tension members employed in the pairs 8 and 9 of pads in the primary tension. The top surface 40 of the forward vertical member 27 is inclined downwardly and rearwardly as shown for instance in Fig. 5 to form a threaded receiving notch 41.

The guide post 25 is held fixed in the block and is between the secondary tension and the horn 19. It is also located forward of surface 31 in front of a line joining the pads 9 and the member 27 so that any thread which is bent forwardly around it will be forward of the longer member 27.

In operation, and assuming that the shuttle is in flight after just having been replenished with a full bobbin B, its thread will extend to the thread holder (not shown) and will occupy the relatively high position shown at H in Fig. 2 and will be between both the primary tension pads 8 and 9 and also between the vertical members 26 and 27 of the secondary tension, see Fig. 6. The tension on this first pick is therefore determined by the primary and secondary tensions. When the shuttle is picked back in the reverse direction the thread will be deflected downwardly by the horn 19 which is a means for lowering the thread and the thread then enters the passage 17 and comes out of the delivery eye D between the posts 15 and 16. When the thread is thus disposed it is below the member 26 and forward of the surface due to the location of the third post 25, see Fig. 7. When in this position the path reversed by the weft is entirely clear of the members 26 and 27 and the tension is determined by the primary tension PT and also the friction offered to movement of the thread by the post 25 and one or the other of the posts 15 or 16, depending upon the direction of travel of the shuttle. This tension is the same as the predetermined tension which had been produced on the first pick of the shuttle by the primary and secondary tensions.

In Fig. 4 it will be seen that the member 26 has a horizontal bottom surface 45 which extends over the weft W and since the surface 31 is in close engagement with the surface 46 of the rear member 27 there is no chance for the weft to pass upwardly and become again engaged between the members 26 and 27. As can be seen in Fig. 4, the lower end 32 and the bottom surface 45 cooperate with each other and the thread block 4 to form a closed passageway for the thread W to prevent the latter from escaping from the shuttle block while at the same time being ineffective to influence the tension of the thread.

In the modified form shown in Fig. 8 all of the parts already described will be substantially the same except that guide post 25a is between the primary and secondary tensions and also forward of surface 31. In the form shown in Fig. 9 the post 25b, similar to post 25, is fixed directly to and depends from the front tension

member 26, being also forward of surface 31 and to one side of the guide pin 34.

From the foregoing it will be seen that the invention sets forth a shuttle tension comprising a primary tension which is operative on the thread for all picks of the shuttle and a secondary tension which is operative on only the first pick following weft replenishment. When the shuttle becomes completely threaded on its return or reverse flight the thread moves downwardly entirely clear of the secondary tension and the stationary posts 25, 25a or 25b and one of the other of the posts 15, 16 will by friction produce a tension equal to that caused by the secondary tension.

Having now particularly described and ascertained the nature of the invention and in what manner the same is to be performed, what is claimed is:

1. In a self-threading shuttle having a thread delivery eye and a pair of thread guide posts associated with and defining part of said eye, a thread block provided with a thread passage and a substantially semi-cylindrical upwardly and rearwardly opening cylindrical pocket communicating with said passage at one end thereof, primary tensioning means located in and at the other end of said passage, secondary tensioning means including a substantially cylindrical member snugly fitting said pocket stationarily with respect to said block and having a rearwardly facing vertical flat tension surface extending into said passage, said secondary tensioning means also including a vertically extending tension member having a forwardly facing vertical flat tension surface for yielding engagement with said first-mentioned surface and movable with respect to said block and said cylindrical member transversely of said passage, both tensioning means cooperating with each other to produce a predetermined tension on the thread on the first pick of the shuttle after weft replenishment thereof, a flat bottom surface on said cylindrical member above the bottom end of said vertically extending tension member to prevent upward movement of the thread to a position between said members, holding means supporting said cylindrical member in fixed position on the shuttle with said bottom surface above the bottom of the thread passage, means on the shuttle effective to move the thread downwardly and out of engagement with the secondary tensioning means on the next pick of the shuttle, and guide means including a third guide post effective on said next and subsequent picks to direct the thread along a path below and under said flat surface of said cylindrical member and forward of said vertically extending tension member thereby causing the thread to be out of contact with both of said members when in said path, the primary tensioning means cooperating with said third post and one or the other of said pair of posts, depending upon the direction of travel of the shuttle, to maintain the thread in said path and to produce said predetermined tension on subsequent picks of the shuttle.

2. The shuttle set forth in claim 1 wherein said cylindrical member has a downwardly and rearwardly inclined flat top surface to form a thread receiving notch with said vertically extending tension member.

3. The shuttle set forth in claim 1 wherein the vertically extending tension member is longer than and extends below said bottom surface of said cylindrical member and has the lower end thereof guidingly mounted on a transverse pin fixed to said block and extending across said passage below said cylindrical member and said path, said lower end and said bottom surface coating with each other and said block to form a closed passage-way for the thread.

4. The shuttle set forth in claim 1 wherein said thread block adjustably mounts a single spring for engagement with said extending tension member to act along a line intermediate the top and bottom of said tension surfaces to urge the tension member against said cylindrical

member to partially close said thread passage to prevent upward movement of the thread out of said passage.

5. The self-threading shuttle set forth in claim 1 wherein in said guide means is a cylindrical post beyond the secondary means with respect to the primary means and forward with respect to said rearwardly facing surface to permit the thread to pass beneath said bottom surface to said path.

6. The self-threading shuttle set forth in claim 1 wherein in said guide means is between said primary and secondary tensioning means and forward of said rearwardly facing surface.

7. The self-threading shuttle in claim 1 wherein the guide means is fixed to and depends from said bottom surface forward of said rearwardly facing surface.
